BLOOD TRANSFUSION APPARATUS

Barney Wandel, Boston, Mass.

Application February 7, 1935, Serial No. 5,449

5 Claims. (Cl. 103—172)

This invention relates to an apparatus primarily adapted for the transfusion of blood from a donor to the recipient in a continuous stream, and is capable of practical use when operated 5 manually or by power, as double acting or single acting.

It is particularly aimed to provide a novel construction wherein a control head is provided to which the barrel or barrels are attached, and 10 which head utilizes valves operating without resort to springs or similar parts.

The more specific objects and advantages will become apparent from a consideration of the description following taken in connection with 15 accompanying drawings illustrating an operative embodiment.

In said drawings:—

Figure 1 is a view in side elevation of the improved transfusion apparatus,

Figure 2 is a top or plan view of said apparatus,

Figure 3 is a central longitudinal sectional view through the apparatus,

Figure 4 is a cross sectional view taken on the line 4—4 of Figure 1,

Figure 5 is a cross sectional view taken on the line 5—5 of Figure 1,

Figure 6 is a sectional view taken on the line 6—6 of Figure 3,

Figure 7 is an enlarged detail longitudinal sectional view through the control head and adjacent parts, taken on the line 7—7 of Figure 4, and

Figure 8 is a view in longitudinal section taken on the line 8—8 of Figure 6.

Referring specifically to the drawings, wherein like reference characters designate like or similar parts, the invention has a central control head as at 10 consisting of a plate 11 against opposite sides of which cup-shaped disks 12, as by means 40 of detachable screws 13, are secured. Through the plate 11 communicating intake chambers 14 are provided, each having an inlet port at 15, to communicating with a manifold chamber 16, to which a passage 17 leads. Passage 17 extends 45 through a nozzle 18 to which a flexible tube or conduit 19 is adapted to be connected and which also is to be placed in communication with the blood stream of the donor. Spherical valves 20 are located one in each chamber 14.

Said control head also has communicating outlet chambers 21 in which spherical valves 22 operate. Said valves 22 coact with outlet ports 23 provided through the plates 12. Also provided 55 through the plates 12 are ports 24 through which

the blood passes from chambers 14 under control of valves 20.

The apparatus has a pair of similar barrels or cylinders 25, preferably of glass, about which metallic rings 26 are attached as by means of cement, and which rings at 27 are detachably screw-threaded into the cup-shaped plates 12.

Metallic pistons 28 are slidably disposed within the barrels or cylinders 25 and a rod 29 extends from each piston, being provided with a knob 30, 10 preferably screw-threaded thereon as at 31. Brackets 32 are rigidly fastened to the rods 29 and such brackets 32 are connected by a connecting rod 33 which extends through openings in the brackets at 34, has pins 35 abutting the 15 brackets, and nuts 36 screw-threaded to the terminals of the connecting rod 33.

Said plate 11 may have an extension as at 37 for connection as by means of a bolt 38 to a bracket 39, of any suitable form and adapted to 20 secure the apparatus to a table or other support.

The apparatus may be operated manually through engagement with the knobs 30. However, the same may also be operated by power. To this end, an electric motor 40 may be used, which 25 through suitable reduction gearing at 41 and a shaft 42 is adapted to drive an eccentric connection 43, having a pin eccentrically arranged as at 44 engaged in an opening 45 provided in the connecting rod. As a result, through operation of 30 the motor, the connecting rod 33 will be reciprocated to reciprocate the pistons 28. Connecting rod 33 passes loosely through opening 46 in the plate 11.

Attention is called to the fact that the inlet 35 valves 20 and outlet valves 22 coact with walls inclined toward their seats so that such valves by gravity normally travel toward their seats and are engaged therewith; hence pressure is necessary to dislodge the valves from their seats.

Presuming operation of the device, operation of the pistons 28 causes the blood to be drawn into the chamber 16 and thence into the chambers 14, the same on the appropriate stroke of the pistons passing into the respective barrels or cylinders 25 and from the same on the opposite stroke of the pistons passing through the ports 23 into the recesses 21 and from the same through a passage 47 in an outlet nozzle 48 of the plate 11, such nozzle having a tube 49 attached thereto and connected with the blood stream of the recipient. As a result the pumping action is double acting and the blood is transfused in a continuous stream.

A stroke indicating mechanism is also provided consisting of a signal member which may be an electric bell 50, or other selected means, in circuit through conductor 51 with a switch member 52 mounted on a suitable bracket 53 or other suitable means, 54 designating the other switch member mounted on spring arm 55 also mounted on the bracket 53, the arm 55 being in circuit with the other terminal of the alarm through conductor 56. Secured on shaft 42 is a cam member 57 that by engaging arm 55 moves the switch members 52 and 53 into contact each half stroke of rod 33 to indicate discharge of the blood in one of the barrels or cylinders 25. A suitable source of electric current for the indicating mechanism is provided, such for instance as the battery 58.

Various changes may be resorted to provided they fall within the spirit and scope of the invention. For instance, the apparatus may be operated as a single action pump. To this end, either of the cylinders or barrels 25 is removed and a plug or imperforate plate screw-threaded into the exposed screw-threads 27. As a result, 25 the single barrel and piston remaining will cause the blood to pass into the barrel through one of the ports 24 and will enter the chamber 21 and be discharged through one of the ports 23.

I claim as my invention:—

1. An apparatus of the class described comprising a supporting plate having an inlet recess and an outlet recess, a disk secured against one side of said plate, said disk having an inlet port and an outlet port in communication with said recesses, control valves for said ports retained in said recesses by said disk, a cylinder extending at a right angle from said plate and connected to and supported by said disk, said cylinder being in communication with said ports, a piston operable 40 in said cylinder, a rod extending from the piston, said rod having a portion disposed exteriorly of the cylinder, a bracket connected to said portion exteriorly of the cylinder, an operating rod located exteriorly of the cylinder in parallelism therewith, said operating rod being slidable relatively to the latter and connected to said bracket, and said plate having a portion extending beyond the cylinder provided with an opening in which the operating rod slides, the plate thus 50 mounting the operating rod against movement about the longitudinal axis of the cylinder.

2. An apparatus of the class described comprising a supporting plate having inlet and outlet recesses, disks secured against opposite sides 55 of said plate, said disks having inlet and outlet ports in communication with said recesses, control valves for said ports and recesses, cylinders extending from opposite sides of the apparatus connected and supported by said disks at a right angle to the plate, said cylinders being in communication with said ports, pistons operable in said cylinders, rods extending from the pistons, each rod having a portion disposed exteriorly of its respective cylinder, a bracket connected to each of said portions exteriorly of the cylinders, and an operating rod located exteriorly of the cylinders, said operating rod being slidable relatively to the latter and joining said brackets.

3. An apparatus of the class described com-

prising a supporting plate having inlet and outlet recesses, disks secured against opposite sides of said plate, said disks having inlet and outlet ports in communication with said recesses, control valves for said ports and recesses, cylinders extending from opposite sides of the apparatus connected and supported by said disks at a right angle to the plate, said cylinders being in communication with said ports, pistons operable in said cylinders, rods extending from the pistons, each rod having a portion disposed exteriorly of its respective cylinder, a bracket connected to each of said portions exteriorly of the cylinders, and an operating rod located exteriorly of the cylinders, said operating rod being slidable relatively to the latter and joining said brackets, said plate having a portion extending laterally beyond the cylinders provided with an opening through which the operating rod slides, the plate thus mounting the operating rod against movement about the longitudinal axis of the cylinders.

4. An apparatus of the class described comprising a supporting plate having inlet and outlet recesses, disks secured against opposite sides of said plate, said disks having inlet and outlet ports in communication with said recesses, control valves for said ports and recesses, cylinders extending from opposite sides of the apparatus connected and supported by said disks at a right angle to the plate, said cylinders being in communication with said ports, pistons operable in said cylinders, rods extending from the pistons, each rod having a portion disposed exteriorly of its respective cylinder, a bracket connected to each of said portions exteriorly of the cylinders, and an operating rod located exteriorly of the cylinders, said operating rod being slidable relatively to the latter and joining said brackets, said operating rod having an opening, and power means provided with an eccentric element engaged in said opening.

5. An apparatus of the class described comprising a supporting plate having inlet and outlet recesses, disks secured against opposite sides of said plate, said disks having inlet and outlet ports in communication with said recesses, control valves for said ports and recesses, cylinders extending from opposite sides of the apparatus connected and supported by said disks at a right angle to the plate, said cylinders being in communication with said ports, pistons operable in said cylinders, rods extending from the pistons, each rod having a portion disposed exteriorly of its respective cylinder, a bracket connected to each of said portions exteriorly of the cylinders, and an operating rod located exteriorly of the cylinders, said operating rod being slidable relatively to the latter and joining said brackets, means removably connecting the operating rod in said brackets, abutment means on the rod engaging the brackets, fastenings on the operating rod engaging the brackets, and said plate having a portion extending laterally beyond the cylinders provided with an opening through which the operating rod slides, the plate thus mounting the operating rod against movement about the longitudinal axis of the cylinders.

BARNEY WANDEL.
